UNITED STATES PATENT OFFICE.

GEORGE E. EVANS, OF WACO, TEXAS.

COTTON GIN.

Continuation of application Serial No. 485,574, filed July 18, 1921. This application filed August 18, 1922. Serial No. 582,633.

To all whom it may concern:

Be it known that I, GEORGE E. EVANS, a citizen of the United States, residing at Waco, in the county of McLennan and State of Texas, have invented certain new and useful Improvements in Cotton Gins, of which the following is a specification.

This invention relates to new and useful improvements in cotton gins.

10 In the cotton gin which has been in common use for the past quarter of a century a single cylinder composed of saws spaced substantially .78 inches apart, is used. These saws project between ribs which have a sufficient pitch at the point where the cotton lint is carried between the same to relieve the seeds, which fall or slide down the ribs between the saws. Working in conjunction with the saw cylinder is a roll box and the seed cotton is fed into this box from the bottom. This box is substantially cylindrical and one side is formed by the ribs which are curved to conform thereto. The saws revolve thru the ribs and project into the 25 box about one and one-fourth inches.

While this style of single saw cylinder gin has proved effective in ginning short staple cotton in which the fibres range in length from .80 to one and one-quarter inches, it has never proven effective in ginning long staple cotton in which the fibres range in length from one and one-quarter to two and one-half inches in length. The roll box is approximately twelve inches in 30 diameter and the saws projecting between the ribs, cut into the roll of seed cotton revolving the same and also removing the lint cotton which is dragged between the ribs and removed therefrom by a brush or 35 air suction. The saws being spaced only about .78 inches apart would cut and break the long staple cotton.

The object of my invention is to provide in conjunction with a roll box a pair of saw cylinders, which are spaced apart and related to the roll box and the ribs thereon in such a manner as to act independently 40 on the roll of seed cotton. A particular object is to arrange the saws of one cylinder in staggered or alternate relation to those of the other cylinder so that the saws of one cylinder will plow different channels in the cotton roll from the saws of the other cylinder. By spacing the saws at a greater 45 distance than .78 inches, a longer staple

may be received therebetween. Also the double saw cylinders acting independently will cause a double action on the roll which will produce a soft, loose and flexible roll.

It is important that each saw cylinder 50 have a separate set of ribs from the other cylinder, with no connection between the saw spaces of one cylinder and the saw spaces of the other cylinder, or that a solid metal bar be interposed between the sets of 55 ribs. Therefore one of the objects is to separate the saw spaces of one set of ribs from the saw spaces of the other set of ribs so as to prevent a continuous slot from one saw cylinder to the other.

A further object is to increase the efficiency and capacity of the gin and to operate on the roll without breaking or twisting the same, either ginning long or short 60 staple cotton.

An important object is to arrange the saws so that those of one cylinder do not intermesh or overlap those of the other cylinder and to space the cylinders at a substantial distance from each other by locating 65 their centers at a distance from each other which is greater than the diameter of either cylinder.

Another object is to superpose the saw cylinders with relation to the roll box and 70 arrange the saw blades of one in staggered relation to the blades of the other cylinder, whereby the lint is properly removed because the staggered relation of the saw blades of the cylinders will act upon the 75 periphery of the roll in the same spaced relation as the usual saw cylinder. By this arrangement the long staple fibres are not engaged with more than one saw simultaneously.

An important advantage resulting from the arrangement of the two saw cylinders is the opportunity to use a short arc or shallow depth within the roll box, whereby a loose, soft and flexible roll, such as is 80 necessary to the most successful ginning, is engendered.

Another object of the invention is to provide means for regulating the revolution of the roll by exerting a tension on the periphery thereof so as to retard said roll or by relieving said tension to release said roll. Such regulation promotes more efficient ginning.

Where it is desired to recover the seed 90

from the particular bale or batch of cotton ginned, and to assure the planter his own seed, immixed with other seed, the invention contemplates the use of an agitator in the roll box which agitator is designed to work out of the gin, all of the seed as soon as the gin feeding is stopped. The agitator is not, however, an essential feature of the invention.

10 A construction designed to carry out the invention will be hereinafter described together with other features of the invention.

The invention will be more readily understood from a reading of the following specification and by reference to the accompanying drawings, in which an example of the invention is shown and wherein:

15 Fig. 1 is a fragmentary transverse vertical sectional view thru a portion of a gin constructed in accordance with my invention,

20 Fig. 2 is a partial longitudinal vertical sectional view on the line 2—2 of Fig. 1, and

25 Fig. 3 is a detail of the roll tension regulator.

In the drawings the numeral 10 designates a roll box. The gin is formed with a huller breast 11, and upper and lower saw cylinders 12 and 13, respectively. A gate 11' controls the admission of cotton to the roll box or diverts it into the huller breast. It is to be understood that the invention is not limited to a hollow gin, but may be used as a plain gin. Each cylinder includes saw blades 14 of the usual type and spacing blocks 15 between the blades. Each cylinder is mounted upon an axial shaft 16 having suitable bearings (not shown) in a casing 17.

30 Ribs of suitable formation are provided and the saw blades extend between the ribs 18 into the roll box, the blades of the cylinder 12 being at the top of the box and 35 the blades of the cylinder 13 at the bottom of the box. As is shown in Fig. 2 the blades of one cylinder are arranged in staggered relation to those of the other cylinder and on centers. It will be noted that for 40 ginning long staple cotton the respective saw blades of a saw cylinder are spaced relatively wide apart as compared with the spacing of the saw of an ordinary gin cylinder, but the saw blades may be spaced 45 in proportion to the lengths of the fibres to be ginned. This wide spacing accommodates a long staple and permits the ginning of cotton without the injury incident to the cutting action of closely spaced saws. 50 However it is possible to use ordinary saw spacing with short staple cotton.

55 By providing two saw cylinders and arranging their blades in staggered relation the roll of cotton in the box 11 is efficiently acted upon. The long staple cotton is not

simultaneously engaged with more than one saw and its injury is thus prevented. The blades extend thru the ribs for a relatively short distance so as to provide a short arc, which is an important feature as it provides for the loose, soft and flexible roll. Although the staggered relation of the saw blades permits of a relatively short arc within the roll box, the pulling power of the saw cylinders will be increased, the saws of the lower cylinder not delinting the seed between them and allowing the saws of the upper cylinder more pulling power than if the saw blades were in vertical alinement.

60 An adjustable tension bar 25 is hinged on a shaft 26 at the upper ends of the ribs and extends longitudinally of the roll box. The lower edge of the bar is disposed to drag on the roll of cotton and by adjusting the bar, so as to vary its pressure upon the roll, the revolution of the latter is more or less varied. The density of the roll may thus be controlled. For adjusting the bar a lever 27 is provided at the end of the shaft and engages a retaining segment on the housing 28 as is shown in Fig. 3. By swinging the lever the bar is adjusted.

65 A wind or deflecting board 19 is adjustably mounted between the saw cylinders, while a similar board 20 is mounted below the cylinder 13. Immediately above the cylinder 12 is mounted a curved deflector plate 21, which acts to deflect the sticks, shale and trash into a mote conveyor 22 which is contiguous to a wind board 23.

70 It is to be understood that the invention may be applied to either a brush gin or an air blast gin as is disclosed in my co-pending application Serial No. 543,253, and the invention is not limited to either style of gin. In this particular application I have chosen to illustrate a brush gin.

75 Relatively between the cylinders I mount an ordinary gin brush 24 and below this is mounted a mote board 29 located at the mouth of a lint flue 30 so that the lint removed from the saws by the brush is directed into this flue.

80 While the essential feature of the invention resides in the two saw cylinders having their blades in staggered relation and the respective blades of a cylinder being spaced proportionately to the length of the fibres to be ginned, long fibres requiring relatively wide spacing, an important feature resides in an agitator 31 within the roll box. This agitator is mounted upon a shaft 32 and includes radially extending fingers and may be rotated in any suitable manner. The agitator causes the discharge of the seed from the roll box during the ginning operation and also completes the discharge of all the seed of a bale before another is fed into the gin. By this means, a planter whose cotton is being ginned is

assured of receiving all of and only his own particular seed, thus a mixture of seed of different planters is prevented and a particular strain of cotton may be kept pure.

5 3. The agitator further provides for cleansing the roll box of sticks and other foreign matter which might otherwise accumulate and positively insures proper rotation of the rolls.

10 4. It is to be noted that the ribs 18 are formed in an upper set and a lower set and the ribs of one set are offset laterally from the ribs of the other set. While it is possible to make the two sets of ribs of a single plate, it is preferable to form the lower set separate from the upper set.

15 5. Good results have been accomplished by spacing the centers of the saw cylinders a distance from each other equal to the diameter of one of the saws plus the length of the longest fibre to be ginned. Also the saws of both cylinders should be of substantially the same diameter. This provides an adequate space between the cylinders and permits the saws of each to project into the same roll box in proper order and location. The lower saw cylinder receives the seed cotton from the huller breast and carries it into the roll box 10 wherein it is freed from the lower saws and becomes part of the roll and is then pulled between the ribs and removed by the air suction.

20 6. It is important that the cylinder centers be spaced far enough apart to permit the saw spaces between the lower set of ribs to terminate before entering or approaching the saw spaces between the upper set of ribs, whereby the upper ribs may be in staggered or alternate relation to the lower ribs with sufficient space therebetween to provide a solid transverse bar or panel of metal between the two sets of ribs. By this arrangement the saws of one cylinder cannot overlap those of another cylinder and a solid obstruction is offered whereby the cotton after having been acted upon in its travel around the roll box. Further the cotton cannot be carried up the saw spaces between the lower ribs and wedged into the saw spaces between the upper ribs.

25 7. While this gin is designed to handle long staple cotton it will also handle short and medium staple cotton with greater efficiency and rapidity than the present gins, now in common use.

80 8. Various changes in the size and shape of the various parts as well as modifications and alterations may be made within the scope of the appended claims.

9. This application is a continuation of my application, Serial No. 485,574 filed July 18, 1921.

10. What I claim is:

15 1. In a cotton gin, a roll box having curved ribs forming one side thereof, said

ribs having an upper set of saw spaces and a lower set of saw spaces in staggered relation to the upper spaces, a transverse bar separating the lower spaces from the upper spaces, a saw cylinder having its blades projecting thru the upper saw spaces of the ribs, a second saw cylinder having its blades projecting thru the lower saw spaces of the ribs, the blades of both saw cylinders projecting into the same roll box, and means for removing lint from the blades of the cylinders. 70 75

2. In a cotton gin, a roll box having curved ribs forming one side thereof, said ribs having an upper set of saw spaces and a lower set of saw spaces entirely separated from the upper set of spaces, said ribs having a continuous transverse bar between their upper and lower saw spaces, a saw cylinder having its blades projecting thru the upper saw spaces of the ribs, a second saw cylinder having its blades projecting thru the lower saw spaces of the ribs, the blades of both cylinders projecting into the same roll box, and means for removing lint from the blades of the cylinders. 80 85 90

3. In a cotton gin, a roll box having curved ribs forming one side thereof, said ribs having an upper set of saw spaces and a lower set of saw spaces entirely separated from the upper set of spaces, said ribs having a continuous transverse bar between their upper and lower saw spaces, a saw cylinder having its blades projecting thru the upper saw spaces of the ribs, a second saw cylinder having its blades projecting thru the lower saw spaces of the ribs, the blades of both cylinders projecting into the same roll box, and means for removing lint from the blades of the cylinders, the saw cylinders being spaced a substantial distance from each other and being free from overlapping, the saw blades being spaced relatively wide apart. 95 100 105

4. In a cotton gin, a roll box, curved ribs forming one side and part of the bottom of said box, the ribs comprising an upper concaved set and a lower concavo-convex set, the saw spaces between the upper set of ribs being in staggered relation to those of the lower set and free from connection therewith, an upper saw cylinder having its blades projecting thru the saw spaces of the upper set of ribs, a lower saw cylinder having its blades projecting thru the saw spaces of the lower set of ribs, both cylinders having their blades projecting into the same roll box, the upper cylinder blades projecting between the concaved ribs and the lower blades projecting between the concavo-convex ribs, and means for removing lint from the blades of the cylinders. 110 115 120 125

5. In a cotton gin, a roll box, curved ribs forming part of said box, a pair of saw cylinders having their blades projecting into

said box in staggered relation and being spaced apart at their nearest approach at least the distance of the length of the longest fibre to be ginned, said saw cylinders acting independently and having their blades spaced in proportion to the length of the fibre to be ginned, and means for removing lint from the blades of the cylinders.

6. In a cotton gin, a roll box having curved ribs forming one side of the box, said ribs having an upper set of saw spaces and a lower set of saw spaces in staggered relation to the upper spaces, a transverse bar separating the lower spaces from the upper spaces, a saw cylinder having its blades projecting thru the upper saw spaces of the ribs, a second saw cylinder having its blades projecting thru the lower saw spaces of the ribs, the blades of both saw cylinders projecting into the same roll box, means for removing lint from the blades of the cylinders, and a transverse tension bar mounted at the upper side of the roll box.

20

removing lint from the blades of the cylinders, and an agitator mounted in the roll box relatively between the saw cylinders.

7. In a cotton gin, a roll box having curved ribs forming one side thereof, said ribs having an upper set of saw spaces and a lower set of saw spaces in staggered relation to the upper spaces, a transverse bar separating the lower spaces from the upper spaces, a saw cylinder having its blades projecting thru the upper saw spaces of the ribs, a second saw cylinder having its blades projecting thru the lower saw spaces of the ribs, the blades of both saw cylinders projecting into the same roll box, means for removing lint from the blades of the cylinders, and a transverse tension bar mounted at the upper side of the roll box.
